UNITED STATES PATENT OFFICE

169,979

GAME BOARD OR SIMILAR ARTICLE

Herman Kesler, Jenkintown, Pa.

Application February 10, 1953, Serial No. 23,530

Term of patent 14 years

(Cl. D34—5)

To all whom it may concern:

Be it known that I, Herman Kesler, a citizen of the United States, residing at Jenkintown, in the county of Montgomery, and State of Pennsylvania, have invented a new, original, and ornamental Design for a Game Board or Similar Article, of which the following is a specification, reference being had to the accompanying drawing forming part thereof:

In the drawing:

Fig. 1 is a top plan view of a game board showing my new design.

Fig. 2 is an end view of the game board.

I claim:

The ornamental design for a game board or similar article, substantially as shown.

HERMAN KESLER.
